ATTORNEY

UNITED STATES PATENT OFFICE

REUBEN ECKSTEIN, OF NEW YORK, N. Y.

ELECTRIC SOCKET

Application filed February 7, 1929. Serial No. 338,148.

This invention relates to electric lighting sets. More particularly the invention is directed to an improved lamp socket construction, adapted to be used in portable lighting outfits for display and ornamental illumination, such as show windows, Christmas tree decorative lighting and other like purposes.

One object of the invention is to provide in portable lighting outfits of the character described, lamp sockets adapted to receive standard screw base lamps in which the conventional metallic screw shell contact is eliminated and in place thereof a novel form of spring contact is provided.

Another object of the invention is to provide a lamp socket construction comprising few and simple parts which are easily and quickly assembled to form a rugged structure, which shall be cheap to manufacture and practical and efficient to a high degree in use.

Other objects of this invention will in part be obvious and in part hereinafter pointed out.

The invention accordingly consists in the features of construction, combinations of elements and arrangements of parts which will be exemplified in the construction hereinafter described and of which the scope of invention will be indicated in the following claims.

In the accompanying drawings in which is shown one of various possible illustrative embodiments of this invention,

Fig. 1 is a front elevational view, partly diagrammatic showing a portable series circuit Christmas tree lighting outfit formed with lamp sockets constructed to embody the invention.

Fig. 2 is a cross-sectional view taken through one of the improved assembled lamp sockets showing the interior construction with a lamp mounted in place.

Fig. 3 is a cross-sectional view of the improved lamp socket showing the parts separated ready for assembly, and

Fig. 4 is a cross-sectional view taken on lines 4-4 in Fig. 2.

Referring in detail to the drawing, 10 denotes a Christmas lighting outfit formed with a plurality of miniature sized lamp sockets 11 constructed to embody the invention, said

sockets may be connected either in series or parallel circuit and as shown in Fig. 1 are connected in series circuit by means of flexible insulated, covered conductor wires 12 to form a conventional type of outfit adapted to be connected to a suitable power supply (not shown) by means of a plug cap 13 in the well understood manner.

One feature of the invention is to provide in a screw type lamp socket, current carrying parts having a spring terminal replacing the usual metallic screw shell contact thereby forming a cheap yet rugged structure which can be easily and quickly assembled as will now be described in detail.

The socket 11 may comprise a suitably molded insulating casing 14 having a chamber 15 of circular cross-section extending in from an open end 14a thereof, said casing being formed with a closed end wall 14b at the bottom of said chamber. The side wall of said chamber 15 extending in from said casing open end 14a has integrally formed therewith a screw thread 15b adapted to receive and engage with the screw base 16 of a standard miniature lamp L.

The usual metallic screw shell contact is entirely eliminated as part of the improved socket 11 and instead the current carrying parts may comprise a helically wound wire spring contact 17 and a spring center contact 18, the latter being mounted on an insulating washer or disc 19. One end 17a of the helical spring contact 17 connects with one of the conductor wires 12 in any suitable manner as by means of a soldered joint 12a. The spring contact 17 is preferably anchored to the washer 19 by passing the contact end 17a through an opening 19a provided in the rim portion of the washer 19 as is clearly shown in Figs. 2 and 3. The other end 17b of the helical spring contact 17 may be formed to provide a seat in which the insulating button 16a terminating the lamp base 16 sits and is proportioned to contact with the metallic screw plug contact 16b of the lamp base 16 as shown in Fig. 2.

The spring center contact 18 passes centrally through a slot 19b provided in the washer 19, the spring terminal end 18a ex-

tending on the upper side of said washer being adapted to connect with the center contact 16c of the lamp base 16. The other terminal end 18b of the contact 18 on the lower side of the washer connects with the other of said conductor wires 12 in any suitable manner as by soldered joint 12b.

The current carrying parts are thus assembled within the socket chamber below the threads 15b with the conductor wires 12 spaced relatively widely apart from each other. The closed end wall 14b of the casing is provided with passages 14c through which the conductor wires 12 extend to connect the socket in circuit.

The assembly of the socket parts will now be apparent. With the conductor wires 12 extended through the passages 14c of the casing 14 as shown in Fig. 3, the helical spring 20 contact 17 and the spring center contact 18 are soldered to the ends of the conductor wires 12, said contacts first being mounted on the washer 19 as described above.

The current carrying parts are next inserted into the casing 14 and housed in the chamber 15 to abut the end wall 14b and below the threads 15b. The socket 11 is now ready to receive the lamp base 16 inserted into the casing opening 14a. The threads 30 15b engage the screw plug contact 16b of the lamp base 16 and on screwing the latter into the chamber 15, the button 16a of the lamp base seats itself on the end 17b of the helical spring contact 17 and connects the base plug contact 16b with the latter. The center contact 16c of the lamp base is simultaneously lowered to connect with the spring end 18a thus completing the circuit of the lamp with the conductor wires 12. The improved socket 11 thus forms a simple structure which eliminates the usual metallic shell contact and provides spring contacts which aid in retaining the lamp from being accidentally loosened in its screw mounting.

It will thus be seen that there is provided apparatus in which the several objects of this invention are achieved and which is well adapted to meet the conditions of practical use.

As various possible embodiments might be made of the above invention and as various changes might be made in the embodiment above set forth, it is to be understood that all matter herein set forth or shown in the accompanying drawing is to be interpreted as illustrative and not in a limiting sense except as to such limits imposed by the scope of the claims.

Having thus described my invention I claim as new and desire to secure by Letters Patent:

1. A lamp socket for connecting to flexible conductors comprising a tubular insulating casing having a closed end wall, said casing formed with an integral thread portion

adapted to receive a screw lamp base and current carrying parts in said casing abutting said wall, said parts including a contact movable axially to and from said threaded portion adapted to connect with the plug contact shell of said lamp base. 70

2. In a lamp socket construction, a casing having an integral threaded portion formed of insulating material adapted to receive a screw lamp base, and a helical resilient current carrying member cooperatively positioned with respect to said casing threaded portion adapted to connect electrically with the plug contact shell of the lamp base engaged with said casing threaded portion. 75

3. A lamp socket construction of the character described adapted to be fitted with a conventional screw base lamp comprising insulating threaded means for engaging with the screw plug contact of said lamp base, and helical spring contact means for electrically connecting with said screw base contact on engaging said lamp with said means. 80

4. In combination, a conventional screw base lamp and a socket having an insulating casing formed with integral threads for engaging with the plug screw contact of said lamp, and a yieldable helical spring contact for connecting with the plug contact shell of the lamp base mounted in said casing to resist entrance of the lamp base into said socket. 85

5. In a socket of the character described, a contact comprising a helically wound current carrying spring having one end thereof formed to constitute a seat for the terminal end of a conventional screw base lamp and insulating means for cooperating with the base of said lamp to seat said terminal end against said spring for electrically connecting the latter with the lamp contact shell. 100

6. A lamp socket of the character described comprising an insulating tubular casing having an enclosing wall at one end and open at the other end to form a chamber, the portions of the wall of said chamber adjacent said opening end being formed with integral threads adapted to receive the screw plug base of a conventional lamp, current carrying members in said chamber below said threads, said members including a helically wound compression spring and a center contact mounted on an insulating washer, said casing wall having spaced passages communicating with said chamber, and conductor wires extending through said passages connecting with said current carrying members. 110

In testimony whereof I affix my signature.

REUBEN ECKSTEIN.
